GENERATOR PROTECTION AGAINST
LEAKAGE OF COOLER TUBES

Ernest I. Pollard, Wilkinsburg, Pa., assignor to
Westinghouse Electric & Manufacturing Company, East Pittsburgh, Pa., a corporation of Pennsylvania

Application April 29, 1942, Serial No. 441,051

3 Claims. (Cl. 171—252)

My invention relates to ventilated dynamo-electric machines, and it has particular relation to marine electrical equipments (generators or motors), which are cooled by a recirculating gaseous cooling-medium, such as air, which passes over water-coolers which circulate sea-water through the tubes of the coolers. The fact that sea-water is salt makes it particularly necessary to safeguard against any possibility of water-leakage into the vital parts of the machine, and on vessels where the utmost reliability of the electrical equipment is required, precautions must be taken to prevent any possibility of the entrance of sea-water into the machine in the event of corrosion or breakage of the pipes of the cooler.

Heretofore, the above-mentioned problem has been solved, at very considerable expense, by the use of double-tube coolers, arranged with the water-tubes inside of other tubes which collect the water which would otherwise drip into the machine in the event of a failure of an inner tube as a result of corrosion or breakage from shell-shock or other cause, an alarm being sounded when the water leaks into the outer tubes. This construction is obviously expensive, of poor heat-transfer efficiency, and of poor space-economy, all of which considerably increases the expense, but heretofore it has been the only solution to the problem in question.

According to my invention, I utilize standard coolers, that is, coolers having single tubes, or just the tubes carrying the cooling water, and I provide a system of baffles for draining away any leakage-water from the vital parts of the machine, while permitting the recirculated cooling-air to pass moderately freely through the system of baffles. This construction is not only very much less expensive than the double-tube cooler-arrangement, saving over one hundred thousand dollars on a single year's business, but it also has the advantage of being more rugged, from the standpoint of shell-shock, which is very important on naval vessels.

With the foregoing and other objects in view, my invention consists in the apparatus, combinations, parts and methods hereinafter described and claimed, and illustrated in the accompanying drawing, wherein

Figure 1 is an end-view, partly in section, showing an alternating-current turbine-generator utilizing my invention;

Fig. 2 is a side-view, partly in section, of the same machine; and

Figs. 3 and 4 are similar views of an alternat-

ing-current motor utilizing a different form of embodiment of my invention.

Figures 1 and 2 illustrate the application of my invention to a very common type of cooler-cooled dynamo-electric machine in which the water-cooler is disposed above the machine. The stator of the machine is shown at 5, consisting of a core having a plurality of radial ventilating-ducts 6, and a stator-winding 7. Separated from the stator by an air-gap 8, is the rotor 9 of the machine. In the form of embodiment of the invention shown in Figs. 1 and 2, the rotor 9 carries a fan or blower-member 11 at each end thereof, and the end-bell space 12, at each end, is provided with air-baffles 13 for directing the return-air into the entrance-portion of the blower 11, and thence into the air-gap 8, and on through the radial vents 6, from which the air is discharged out of the vital electrical parts of the machine.

Disposed on top of the stator-member 5 is a water-cooler 15, illustrated as comprising a series of pipes 16 extending horizontally between headers 17 and 18, with inlet and outlet pipes 19 and 20 for the cooling water, usually sea-water on marine applications. An outer housing-structure 22 is provided for taking the air, which is discharged radially outwardly from the machine, and passing it upwardly through the tubes 16 of the cooler 5, and then bringing the air back, through the two end-bell spaces 12 of the machine, into the respective blowers 11, thus completing the recirculating path for the air.

In accordance with my invention, as shown in Figs. 1 and 2, I provide baffle-means for preventing any accidental leakage of water from the cooler-tubes 16 from flowing back through the radial ventilating ducts 6 of the machine, and on into the vital parts of the machine, producing corrosion and short-circuits. I accomplish this function by suitable baffle-means disposed so as to catch any water leaking from the cooler 15, and draining it away from the vital parts of the machine, as into a trough 24 which is shown in Fig. 1. The particular baffle-means, which is shown in Figs. 1 and 2, for the purpose just mentioned, consists of a series of baffles illustrated as comprising a central convex or inclined baffle 26, disposed above the stator-member 5 and below

the cooler 15, for draining the water to either side of the machine, and an inclined system of louvers, comprising vertically spaced and overlapping slats or other short baffles 27, at each side of the machine, for catching the water which drains off of the ends of the central baffle 26, and

carrying it far enough to the side, or horizontally, so that the water will finally drip into the draining-trough 24. While the inclined baffle-means 26-27 thus effectively drains any downwardly dripping leakage-water horizontally away from the vital parts of the machine, the system of louvered baffles is at the same time sufficiently open, vertically, to permit a moderately free passage of the recirculated cooling-air in an approximately horizontal direction through the louvered baffle-means, the air-circulating path being indicated by arrows in Figs. 1 and 2.

In Figs. 3 and 4, I have illustrated the application of my invention to a somewhat different cooler-arrangement which is also commonly used, in which the cooler is disposed at one side of the dynamo-electric machine which is being cooled. In this form of embodiment of my invention, the machine is illustrated as a large synchronous motor, comprising a stator-core 30 having a plurality of radial ventilating-ducts 31 therein, and an armature-winding 32 carried by said stator-core. The rotor-member 33 is separated from the stator-member 30 by a small air-gap 34, and the rotor-member is illustrated as comprising a spider 35 carrying a rim-member 36 having a plurality of pole-pieces 37 disposed around its circumference, said pole-pieces terminating at the air-gap 34.

The rotation of the rotor-member 33 in Fig. 4 causes a radial flow of air radially outwardly through the radial vents 31 of the stator-core 30, after which the air flows into annular passages 38 which are provided in the supporting frame-structure 39 of the stator-member. At the top of this supporting frame-structure 39, there is provided a rectangular air-housing 41, into which all of the air which is discharged from the stator-ducts 31, all the way around the machine, is discharged, as indicated by the arrows 42. The air-housing 41 carries this air laterally of the machine, and discharges it down through a water-cooler 15', which may be more or less similar to the water-cooler of Figs. 1 and 2, after which the cooled air continues to move downwardly into an air-chamber 44 which contains a series of vertically spaced or louvered baffles 45, an air-blower 46, and suitable ducts or guides 48 for directing the air again into the rotor-member 33, thus completing the recirculating air-system of the motor. The baffles 45 are disposed in a position beneath the cooler 15' and above the blower 46, in such manner as to cause the approximately horizontally moving air to enter the blower through the spaces between the vertically spaced baffles, in a tortuous path which does not greatly impede the air-flow, while effectively draining all downwardly dropping water horizontally away from the blower 46, and thence horizontally away from the duct-system 48 which leads into the vital parts of the electric machine.

While I have described my invention in two specific forms of embodiment, which at present appear to be preferable, it will be readily understood, by those skilled in the art, that many changes may be adopted without departing from the essential spirit of my invention. I desire, therefore, that the appended claims be accorded the broadest construction consistent with their language.

I claim as my invention:

1. A ventilated dynamo-electric machine comprising, in combination with the machine, means for providing a closed recirculating path for a recirculated gaseous cooling-medium for cooling the machine, a cooler of a type using a liquid cooling-medium and conduit-means for said liquid cooling-medium separate from the gaseous cooling-medium, said cooler being disposed above a vital part of the machine and in the path of said recirculated gaseous cooling-medium, and baffle-means disposed underneath said cooler and including an inclined system of louvers comprising vertically spaced and overlapping slats, said inclined system of louvers being disposed in the path of said recirculated gaseous cooling-medium in a position below said cooler in such manner as to permit a moderately free passage of the gaseous cooling-medium in a substantially horizontal direction through the louvers, while draining any downwardly dropping leakage-liquid from the cooler horizontally away from the vital parts of the machine.

2. In combination, a dynamo-electric machine having a gaseous cooling-medium, an enclosure therefor, and a recirculating and cooling means for said gaseous cooling-medium, said recirculating and cooling means including a cooler having a liquid cooling-medium therein, said cooler being located in such elevated position adjacent to the machine that any leakage of liquid therefrom would tend to flow into a vital part of the machine, said recirculating and cooling means causing the gaseous cooling-medium to leave the machine and then pass over said cooler and subsequently return to the machine, said recirculating and cooling means also including a system of vertically spaced, louvered draining-baffles disposed under the cooler in such manner as to permit a moderately free passage of the gaseous cooling-medium in an approximately horizontal direction away from the machine and thence upwardly into the cooler after passing through said baffles, while draining any downwardly dropping leakage-liquid from the cooler horizontally away from possible leakage into the vital parts of the machine.

3. In combination, a dynamo-electric machine having a gaseous cooling-medium, an enclosure therefor, and a recirculating and cooling means for said gaseous cooling-medium, said recirculating and cooling means including a cooler having a liquid cooling-medium therein, said cooler being located over the machine, said recirculating and cooling means causing the gaseous cooling-medium to leave the machine and then pass over said cooler and subsequently return to the machine, said recirculating and cooling means also including a system of vertically spaced, louvered draining-baffles disposed under the cooler in such manner as to permit a moderately free passage of the gaseous cooling-medium in an approximately horizontal direction away from the machine and thence upwardly into the cooler after passing through said baffles, while draining any downwardly dropping leakage-liquid from the cooler horizontally away from possible leakage into the machine.

ERNEST I. POLLARD.
